UNITED STATES PATENT OFFICE

CHAUNCEY E. WALTMAN, OF CHICAGO, ILLINOIS, ASSIGNOR TO I. TEGER, DOING
BUSINESS AS IMPERIAL LAMP MFG. CO., OF CHICAGO, ILLINOIS

DESIGN FOR A SMOKER'S STAND

Application filed January 22, 1930. Serial No. 34,217. Term of patent 3½ years.

To all whom it may concern:

Be it known that I, CHAUNCEY E. WALTMAN, a citizen of the United States, and a resident of Chicago, in the county of Cook and State of Illinois, have invented a new, original, and ornamental Design for a Smoker's Stand, of which the following is a specification, reference being had to the accompanying drawing, forming part thereof.

Fig. 1 is a front view of the stand;
Fig. 2 is a side view;
Fig. 3 is a top plan view; and
Fig. 4 is a horizontal section on the line 4—4 of Fig. 1.

I claim:

The ornamental design for a smoker's stand as shown.

CHAUNCEY E. WALTMAN.
